[57] CLAIM

The ornamental design for a hose nozzle, as shown and described.

DESCRIPTION

FIG. 1 is a perspective view looking at the front and left side of a hose nozzle showing a small hand embodiment of my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view similar to FIG. 1 of a hose nozzle showing a large hand embodiment of my new design;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof, and,

FIG. 14 is a bottom plan view thereof.
